VENTILATOR

Gillette V. Patterson, Howard County, Ind., assignor to Swartwout Fabricators, Inc., Kokomo, Ind.

Continuation of design applications Ser. Nos. 65,025 and 65,026, May 4, 1961. This application Feb. 1, 1962,
Ser. No. 68,607

Term of patent 14 years

(Cl. D62—3)

Fig. 1

Fig. 2

Fig. 3

Fig. 5

FIGURE 5 is a perspective view of a modified form thereof rotated 90°, the side not shown being substantially the same in appearance as that shown.

This application is a continuation of my copending applications Serial Nos. D-65,025 and D-65,026 filed May 4, 1961.

I claim:

The ornamental design for a ventilator, as shown and described.
